MACHINE FOR CROCHETING SHEATHINGS
ABOUT CORES

Peter F. Nardulli, Chicago, Ill., assignor to Consolidated Trimming Corporation, New York, N. Y., a corporation of New York

Application March 2, 1942, Serial No. 433,101

20 Claims. (Cl. 66—1)

This invention relates to a method of and means for crocheting a sheath about a ring such as, for instance, a shade pull ring, a curtain ring, a tassel ring or the like. The particular embodiment of the present invention is exemplified in a machine for making a well known type of ring, to-wit, the ring which is the product of the machine of the Patent No. 1,965,298 issued to myself and Michael J. Nardulli, July 3, 1934.

In the crocheting of a sheathing about a ring the formation of each stitch involves a cycle of operations, many steps of which cycle are not continuous. Parts must be brought into motion, reach their maximum velocity and then brought back to rest one or more times during each complete cycle of operations. In a high speed machine the time for making a complete sheathing about a ring, from the first stitch to the completion of the last stitch, may be appreciably less than ten seconds. There may be more than thirty complete stitches per ring which will allow less than one-third of a second for the completion of each stitch. The completion of a stitch may require from two to four successive operating steps, which would allow appreciably less than one-sixth of a second for the completion of one of the operating steps. Certain parts of the machine must be started from a position of rest, moved in a certain manner and then brought back to rest, all within a time appreciably less than one-sixth of a second. It is thus apparent that in order to obtain high speed operation the moving parts that have such motion imparted thereto must be made exceedingly light in weight and should not be vastly out of dynamic balance. I have found that it is difficult, if not impossible, to obtain such high speeds of operation where the part which must go through such a cycle of operations during a fraction of each stitch consists of the ring and its associated holder. The very mass of the holder inhibits any such sharp acceleration and deceleration as would be required to attain that speed of motion. I have discovered that the desired movement can be obtained by turning the crocheting hook rather than by turning the ring holder. Since the crocheting hook is light in weight it can very quickly be moved from one position to another and back again.

In accordance with the principles of one embodiment of the present invention the ring to be sheathed is placed in a stationary holder and the crocheting hook is reciprocated to and from the holder, the crocheting hook passing through the ring during one forward stroke in the stitch

forming operation and being shifted to pass outside of the ring during the next forward stroke. The cord to be crocheted is continuously rotated in synchronism with the movement of the crocheting hook so that the cord is in a position to be picked up by the hook when the hook commences its rearward stroke from either one of its alternate positions.

The attainment of the above and further objects of the present invention will be apparent from the following specification taken in conjunction with the accompanying drawings forming a part thereof.

In the drawings:

15 Figures 1, 2, 3 and 4 are diagrammatic views illustrating four successive steps in the process of crocheting a stitch about a ring to be sheathed;

20 Figure 5 is a plan view of a machine for crocheting a sheathing about a ring in accordance with the process of Figures 1 to 4; and

25 Figure 6 is a side view of the machine of Figure 5.

Like reference numerals indicate like parts throughout the various figures of drawings.

Reference may now be had more particularly to Figures 1 to 4 inclusive. A ring to be sheathed is indicated at 1. This ring is supported in the inclined position illustrated, in a manner to be more fully described as this specification proceeds, it being sufficient for the present purposes to state that the holder for the ring is stationary and holds the ring at the inclination shown but permits free turning of the ring about the central axis 2 of the holder. A well known standard latch type crocheting hook or crocheting needle is indicated at 4. This crocheting hook comprises a wire shank 5 having a hook 6 at its forward end and a latch 7 pivoted thereto and freely swingable towards and away from the hook 6. This type of crocheting hook or needle is well known in the art and forms no part of the present invention except in the combination with the machine. A cord feeding tube or looper 10 is mounted for rotation about its center longitudinal axis 11 and has a short tubular section 12 at the end thereof and at an angle thereto, said section 12 constituting a cord feeding member. The cord to be crocheted, indicated at 15, extends from a reel, through a usual cord tensioning device, thence through the tube 10 and cord feeding member 12, through which it is pulled during the crocheting operations in a manner to be presently set forth. The tube 10 is of appreciably greater diameter than the cord to prevent any

possibility of binding of the cord in the tube. The section 12 is of smaller diameter, especially at the open end which constitutes the outlet thereof, but yet of sufficiently large diameter to prevent binding the cord in said section.

To commence the crocheting operations the cord 15 is looped around the hook 6, as illustrated in Figure 1, and the far end 17 of the cord is held manually. The crocheting hook is then rotated through an angle of approximately 130° about the axis 11 parallel to but spaced from the longitudinal axis of the shank 5. This brings the needle into the position illustrated in Figure 2 with the cord 15 looped around the hook of the crocheting hook. At this time the bottom of the shank 5 is slightly above the bottom opening in the ring 1. The latch 7 may remain open or it may move by gravity to the closed position during the turning of the hook. The position of the latch at this time is, however, of no importance. If the latch is not open when the mechanism is in the position illustrated in Figure 2 it will be positively open during the next step in the operation of the mechanism. The cord feeding tube 10 rotates about its axis 11 from the position illustrated in Figure 1 towards the position illustrated in Figure 3 and the crocheting hook 4 commences to move forward. In its forward movement the hook 6 passes through the ring 1, and the loop 18 on the crocheting hook slides along the shank 5, thus forcing the latch 7 to its full open position if it is not already in that position and the open latch slides forward through the loop 18, leaving the loop on the shank 5. The mechanism then reaches the position illustrated in Figure 3 and the loop 18 encircles the shank 5 of the crocheting hook. The tube 12 of the looper 10, in its rotation about the axis 11 loops the cord over the crocheting hook or moves the cord into a position in the path of the return movement of the crocheting hook. As the crocheting hook commences its rearward stroke the hook 6 picks up the cord 15 and draws it through the ring 1. The latch 7 is now in its open position, as illustrated in Figure 3, and it therefore passes above the loop 18. As the crocheting hook continues its rearward motion the loop 18 on the shank 5 of the crocheting hook forces the latch 7 to its closed position thus enclosing the loop that is in the hook 6, and then the crocheting hook is pulled through the loop 18, thus casting off the loop 18. The mechanism is now in the position illustrated in Figure 4, which is the position upon the completion of the first stitch. The crocheting hook now rotates back to the position illustrated in Figure 1 and has a loop around the hook 6. The crocheting hook 6 then again moves forward, this time beneath the bottom of the ring 1. As it moves forward the loop 20 in the hook rides on the shank 5, opens the latch 7 in much the same manner as did the loop 18 in moving from the position illustrated in Figure 2 to that illustrated in Figure 3. At that time the cord feeding member comes into the position of Figure 1 placing the cord from the member 12 in the path of the reverse movement of the crocheting hook 6. The crocheting hook then picks up another stitch from the cord 15 and is retracted to the position illustrated in Figure 1. It is to be noted that in this retracted position, which is the position of Figure 1, the crocheting hook is not pulled back as far as it is in Figure 4. In the position of Figure 1 the crocheting hook is not drawn far enough to cast off the previously formed loop on the shank 5. When the

crocheting hook rotates to the position illustrated in Figure 2, on all stitches after the first stitch, there is an additional loop around the shank 5 of the crocheting hook, so that upon the next forward movement of the crocheting hook, which is the movement through the ring 1, there will be two loops on the shank 5 of the crocheting hook. This will be true in every subsequent forward movement of the crocheting hook through the ring 1. Thus in the first stitch the stroke from Figure 3 to Figure 4 is through only one loop 18 whereas on every subsequent stitch around the ring the corresponding stroke is through two loops.

An explanation will now be given of the construction of the machine for performing the stitching operations thus far described. The machine includes a base 49 having a pair of standards 41-42 secured thereto and supporting bearings for a main operating shaft 43. This shaft is power rotated, always in the same direction, in any desired manner, as for instance, by an electric motor or by a clutch and pulley from a common driving shaft that drives a number of such machines. The main drive shaft 43 carries a cam 44 keyed thereto and having a cam groove 45 for imparting the desired motion to a roller type cam follower 46. The cam follower 46 is secured to the underside of a slide shaft 47 that is mounted for longitudinal reciprocation on the standards 41-42. To keep the slide shaft from turning during its reciprocating motion a guide roller 48 is secured thereto in any desired manner, as by a screw 49. The guide roller 48 rides between two guide rods 50-50 that are secured to the tops of the standards 41-42 as by bolts 51-51. As the main operating shaft 43 rotates it rotates the cam 44 so that the cam groove 45 imparts a longitudinal motion to the slide shaft 47 while at the same time the slide shaft is definitely held against rotation. The longitudinal position of the shaft 47 is thus determined by the cam groove 45.

A crocheting hook carriage 55 is mounted in the forward end of the shaft 47 so as to be freely rotatable with respect to the shaft 47 about the longitudinal axis of the crocheting hook carriage. The crocheting hook carriage 55 is slidable through a pinion 58 on the carriage. The pinion 58 is held against longitudinal motion by a pair of side plates 59-59 held between a pair of stationary bars 60-60. The pinion 58 is splined to the crocheting hook carriage 55 so that rotation of the pinion will produce corresponding rotation of the carriage but the carriage may slide longitudinally through the pinion without moving the pinion and without interference by the pinion.

The gear teeth of the pinion 58 are in mesh with teeth on a rack 63 on the upper surface of a longitudinally slidable bar 64. Upon sliding of the bar 64 in one direction or the other the pinion 58 is rotated to rotate the crocheting hook carriage. At the same time the carriage may be moved longitudinally by the shaft 47 actuated by the cam 44.

The forward end of the crocheting hook carriage 55 is slotted, as indicated at 66, to receive the crocheting hook 4. For this purpose the shank 5 of the crocheting hook has a bend therein, as indicated at 68, which fits snugly in a hole 69 in the carriage. The bend in the wire is held by a set screw against dropping from the carriage during rotation of the carriage. Thus the crocheting hook may be reciprocated and rotated by the

corresponding reciprocation and rotation of the carriage 55.

An explanation will now be given of the manner of actuating the rack bar 64 to rotate the crochet hook carriage. For this purpose the main operating shaft 43 extends lengthwise of the machine and carries a sprocket wheel at its outer end which engages a sprocket chain 72 that drives a sprocket wheel keyed to a shaft 73, thereby driving the shaft 73. This shaft 73 is located above the shaft 43, as may be seen from Figure 7, and to the rear thereof, as may be seen from Figure 6. The shaft 73 is journaled in bearings carried by suitable standards secured to the base 40 of the machine. The shaft 73 carries a cam 76 having a cam groove 77 therein in which rides a cam follower 78 in the form of a roller secured to a fitting 79 at the end of the rack bar 64. Thus as the main operating shaft 43 rotates it imparts rectilinear motion to the crochet hook carriage by way of the cam 44 and it imparts rotary motion to the carriage by way of the cam 76 and rack 64, the rotary and rectilinear motions being thus definitely synchronized, as determined by the contours of the two cams.

The main drive shaft 43 has a driving gear 85 keyed thereto which drives an idler gear 86 that in turn drives a gear 87 through which the cord feeding tube 10 extends and to which the tube is secured. The tube 10 is rotated about the center of the gear 87, about the longitudinal axis 11 of the tube as a center, said tube being journaled in suitable supporting bearings in vertically extending side rails 88 secured to the base 40. The gear ratio between the shaft 43 and the tube 10 is such that the tube makes two complete revolutions for each revolution of the shaft 43.

A post 90 is secured to the base 40 and extends upwardly therefrom and at its upper end supports the means for receiving and holding the ring to be sheathed. The ring holding means includes an inclined base 91 bolted or otherwise suitably secured to the post 90. A short cylindrical tube 92 is welded or otherwise rigidly secured to the base 91 and extends at right angles thereto. The tube 92 is of an outside diameter slightly less than the intended inside diameter of a sheathed ring, and is of a height slightly in excess of the intended thickness of a sheathed ring. A cover plate 93 is pivoted on the base 91 and is adapted to be swung clockwise about its hinge 94 from the closed position illustrated in Figure 6 to an open position. A pair of torsion springs 95 on opposite sides of the pivot continuously urge the cover plate 93 upwardly to its open position, that is, in a direction clockwise from that seen in Figure 6. A manually operated pivoted latch 96 is provided for holding the cover in the closed position illustrated in Figure 6. The base 91 and the ring 92 and the cover 93 each have a slot formed therein, as illustrated at 98, through which the crochet hook moves.

The cam 44 is so constructed that for every complete revolution of that cam the shaft 47 makes two complete forward strokes and two complete rearward strokes. As the cam rotates 90° from the position illustrated the crochet hook carriage makes its rearward stroke. During the rearward movement of the shaft 47 the cam 76 is rotated but the shape of the cam groove 77 at the portion thereof then engaged by the follower 78 is a circular arc centered about the center of rotation of the cam, so that the cam imparts no motion to the rack bar 64. When the

shaft 47 reaches its limit of rearward motion there is a period of dwell of the shaft 47 before it commences its next forward motion, this period of dwell being determined by the shape of the cam groove 45 at the portion 81 of the cam 44. During this short period of dwell in the reciprocating movement of the shaft 47 the continued rotation of the cam 76 imparts movement to the rack bar 64 to move the rack 63 to turn the pinion 58 through an angle of approximately 180°. The movement of the rack bar 64 is preferably completed during the period of dwell while the cam follower 46 is on the portion 81 of the cam 44, although this is not indispensable, since if the rotation is not completed during the period of dwell it may continue during the subsequent longitudinal movement of the shaft 47. The shaft 47 then commences its forward movement. During the forward movement of the shaft 47 the cam 76 is rotating, but the curve of the cam surface engaged by the cam follower is a circular arc centered about the center of rotation of the cam. Hence no motion is imparted to the cam follower 78. When the shaft 47 again reaches its furthermost limit of travel and before it commences its rearward motion there is again a period of dwell in the longitudinal motion of the shaft. During this period of dwell a cord is looped around the hook 6. The shaft then commences its rearward motion. During the forward and rearward motion of the shaft 47 the cam 77 does not actuate the follower 78, hence there is no rotation of the crochet hook. When the crochet hook again reaches its limit of rearward motion there is again a period of dwell in the longitudinal movement during which period the cam 76 actuates the follower 78 to rotate the crochet hook carriage through an angle equal to and opposite that of its former rotation. Upon completion of that rotation the forward motion of the shaft 47 again commences and continues until the crochet hook is again in the position illustrated in the drawings. This completes two forward and two rearward strokes of the crochet hook which is a complete cycle in the formation of a single stitch. This cycle is repeated for each stitch.

It is to be noted that in the cycle of operations of the machine there is one rearward stroke of the crochet hook to withdraw the hook from within the ring and there is one rearward stroke to withdraw the crochet hook from beneath the ring. The former stroke is made longer than the latter stroke, for a definite purpose. During the rearward stroke in which the crochet hook is withdrawn from within the ring the rearward movement must be of such length as to withdraw the crocheting hook from within the loop or loops on the shank 5. This casts off the one or the two previously formed loops from the shank 5 of the crocheting hook but leaves a loop formed around the hook portion 6 of the needle. When the needle is rotated 180° after casting off the loops previously formed on the shank 5 and is then advanced below the ring 1 the shank 5 moves past the loop in the hook 6 so that the loop opens the latch 7 and then comes to rest on the shank 5. The next loop to be formed on the hook 6 is not to be drawn through the previous loop on the shank 5 and therefore upon rearward movement of the crocheting needle while it is below the ring 1 the crocheting needle stops short of the position where it would cast off the previously formed loop on the shank 5.

As a result, when the needle is then rotated upwardly and thereafter moved forwardly the loop on the hook 6 is then positioned on the shank 5 in addition to the loop previously on the shank.

In order to provide the difference in length of stroke on the two rearward strokes of the needle the cam groove 45 is not perfectly symmetrical. The portion 81 of the cam groove that determines the extent of rearward movement of the crochet hook when the crochet hook is in its upper position is further back than the portion 83 of the cam groove, which is spaced 180° from the portion 81 and which determines the distance of retraction of the crochet hook when the crochet hook is in its inverted position. This difference in distance is quite small, of the order of $\frac{3}{16}$ of an inch in one embodiment of the present invention. It is this last amount of rearward travel of the needle from the position illustrated in Figure 6 which results in the casting off of the loops previously formed on the shank 5 of the crocheting needle.

To start the machine, the end of a cord to be crocheted is drawn from its reel, extended through a constant tensioning device, not shown, to maintain a proper tension on the cord, and is then threaded through the tube 16, with the end of the cord coming out through the open end of the tubular cord feeding member 12. The latch 96 is then moved to its unlatching position whereupon the cover 93 immediately opens, under the action of the springs 95. The operator then inserts a metallic ring 1 to be sheathed, over the tube 92, and then manually closes the cover 93 and latches it closed by means of the latch 96. The crochet hook of the machine is at that time retracted from the position illustrated in Figure 6 and is in its inverted position so that the next movement of the crochet hook will be a rotation of 180° to bring the crochet hook to its uppermost position to be then followed by a forward movement of the crochet hook. With the crochet hook in the inverted position the operator loops the end of the thread around the hook 6, as illustrated in Figure 1, holds the end 17 of the cord manually and then starts the operation of the main operating shaft 43. The operator allows only a very short length of the free end 17 of the cord, which short length is subsequently concealed by the crocheted loops formed by the machine. Upon completion of the requisite number of stitches, to complete the sheathing around the ring, the operator stops the machine, removes the ring, cuts off the end of the cord and knots it to prevent unraveling, all in a manner well known in the art.

From the above description it is apparent that I have provided a machine of great simplicity. The crochet hook and the feeder are the only two moving parts of the machine (including, of course, the mechanisms for actuating them). Of these parts the cord feeding member 12 has a simple and continuous rotary motion and the crochet hook has alternate turning and reciprocating motions. The ring holder remains stationary throughout the entire operation of the machine. As each stitch is cast off and the crochet hook draws the cord for formation of the next stitch the tension on the cord tightens the last previously cast off stitch to a predetermined and fixed tension, and the pull upon the last cast off stitch is sufficient to cause the ring being sheathed to be turned through a small angle, to-wit, an angle equal to the peripheral extent of one complete stitch. The ring is thus advanced stitch by stitch following the casting off of each

completed stitch, by the tension of the cord itself, without the introduction of any moving parts for accomplishing this result. The ordinary reciprocating action of the crochet hook to draw the cord through the feeder tube 12, as the crochet hook moves following the casting off of the previously formed loops, constitutes the motivating force for turning the ring.

In compliance with the requirements of the patent statutes I have here shown and described a preferred embodiment of my invention. It is, however, to be understood that the invention is not limited to the precise construction here shown, the same being merely illustrative of the principles of the invention. What I consider new and desire to secure by Letters Patent is:

1. A machine of the character described comprising means for supporting an element to be sheathed in the same plane throughout the sheathing thereof, a crocheting hook, mechanism cooperating with said hook to crochet a cord about said element, means for driving said hook and mechanism, said hook and mechanism being so correlated that the hook completes its cycle in four strokes in the formation of one crochet stitch, and means for turning the hook about an axis parallel to but spaced from the longitudinal axis of the hook for shifting the path of movement of the hook from one side of the element to the other side thereof for alternate strokes of the hook in the same direction.

2. A machine of the character described comprising means for supporting an element to be sheathed in the same plane throughout the sheathing thereof, a crocheting hook, mechanism cooperating with said hook to crochet a cord about said element, means for driving said hook and mechanism, said hook and mechanism being so correlated that the hook completes its cycle in four strokes in the formation of one crochet stitch, alternate strokes of the hook in the same direction being of a length insufficient to cast off a previously formed loop on the hook whereby a second loop is subsequently formed on the hook and the intervening alternate strokes in the same direction being of greater length and sufficient to withdraw the hook from the two accumulated loops thereon to cast off said loops.

3. A machine of the character described comprising means for supporting an element to be sheathed, a crocheting hook, mechanism cooperating with said hook to crochet a cord about said element, means for driving said hook and mechanism, said hook and mechanism being so correlated that the hook completes its cycle in four strokes in the formation of one crochet stitch, alternate strokes of the hook in the same direction being of a length insufficient to cast off a previously formed loop on the hook whereby a second loop is subsequently formed on the hook and the intervening alternate strokes in the same direction being of greater length and sufficient to withdraw the hook from the two accumulated loops thereon, and means for turning the hook about an axis parallel to but spaced from the longitudinal axis of the crocheting hook for shifting the path of movement of the hook from one side of the element to the other side thereof for alternate strokes of the hook in the same direction.

4. In a machine of the character described, a holder for an element to be sheathed, a crochet hook, a cord feeding member adjacent the element to be sheathed, means for turning the member to bring the cord feeding part thereof

first on one side and then on the other side of that edge of the element about which a sheath is to be crocheted while maintaining the path of movement of the feeding end of the member always on the same side of the element, means for reciprocating the hook, and means for shifting the path of reciprocation of the hook from one side to the other of that edge of the element about which a sheath is to be crocheted.

5. In a machine of the character described, a holder for a ring to be sheathed, a crochet hook, a cord feeding member the cord feeding end of which is adjacent a ring to be sheathed, means for reciprocating the crochet hook and for shifting the path of reciprocation from one side of the core to the other side of the core on alternate strokes of the hook in the same direction, and means for moving the cord feeding end of the member always outside of the ring to bring the cord into both paths of movement of the hook to correlation to the movement of the hook to crochet a cord about the ring.

6. In a machine for forming a sheath around a core, means for supporting a core, a crocheting hook, mechanism cooperating with said hook to crochet a cord about said core, said mechanism including means for reciprocating the hook and including means for rotating the hook about an axis parallel to the direction of reciprocation of the hook to shift the path of reciprocation of the hook from one side of the core to the other side of the core for alternate reciprocations so that on one to and fro movement the hook passes on one side of the core and on the succeeding to and fro movement the hook passes on the other side of the core.

7. In a machine of the character described, a holder for a ring to be sheathed, a crochet hook, a cord feeding member comprising a rotatable looper the end of which is adjacent a ring to be sheathed, means for reciprocating the crochet hook and for shifting the path of reciprocation from one side of the ring to the other side of the ring on alternate strokes of the crochet hook in the same direction, and means for rotating the looper to bring the cord thereof into the respective paths of movement of the hook in correlation to the movement of the hook to loop the cord around the hook.

8. In a machine for forming a sheath about a core, a rotatable looper, a crochet hook, means for reciprocating the hook towards and from the looper, means for shifting the path of reciprocation of the crochet hook, means for positioning a core to be sheathed between the two paths of reciprocation of the crochet hook, and means for rotating the looper to bring the cord to be crocheted into the two paths of movement of the crochet hook in correlation to the movement of the hook to crochet a cord about the core.

9. In a machine for crocheting a sheath around a core, means for supporting a core, a crocheting hook, mechanism cooperating with said hook to crochet a cord about said core, said mechanism including means for reciprocating the hook, means for shifting the path of reciprocation of the hook from one side of the core to the other side of the core upon alternate reciprocations thereof, a rotatable looper adjacent the foremost position of the crocheting hook, and means for rotating the looper to loop a cord around the crocheting hook each time the crocheting hook is adjacent its foremost position.

10. In a machine for crocheting a sheath about a core, means for supporting a core, a crocheting hook, means for reciprocating the crocheting hook, and means for rotating the crocheting hook about an axis substantially parallel to the direction of reciprocation thereof with an interval of dwell between successive rotations which interval of dwell is substantially greater than the interval of rotation and approximately the same as the time of reciprocation of the hook.

11. In a machine for crocheting a sheath about a core, means for supporting a core, a crocheting hook, means for reciprocating the crocheting hook with a period of dwell at the end of each direction of travel of the crocheting hook, means for rotating the hook about an axis parallel to the longitudinal axis of the hook during the period of dwell at one end of the stroke of the crocheting hook, and means for looping a cord around the crocheting hook during the period of dwell at the other end of the stroke of the crocheting hook.

12. In a machine for crocheting a sheath about a core, a crocheting hook, means for reciprocating the crocheting hook in a direction substantially axially of the hook, and means for turning the crochet hook about an axis substantially parallel to the direction of reciprocation.

13. In a machine for crocheting a sheath about a core, a crocheting hook, means for rotating the crocheting hook about an axis substantially parallel to the longitudinal axis of the crocheting hook with a period of dwell between successive rotations, the interval of dwell being substantially greater than the interval of rotation, and means for reciprocating the crocheting hook during substantially the entire period of dwell in the rotation of the crocheting hook.

14. In a machine for crocheting a sheath about a core, a crocheting hook, means for reciprocating the crocheting hook in a direction substantially axially of the hook with a period of dwell at the end of each reciprocation in one direction, and means for shifting the crocheting hook in one direction during alternate periods of dwell and returning it from its shifted position during the intervening periods of dwell whereby the crocheting hook has two paths of reciprocation, and means supporting a ring to be sheathed with the opening of the ring intersected by only one of those paths.

15. In a machine for crocheting a sheath about a ring, means for supporting a ring to be sheathed, a reciprocating crocheting hook, means for reciprocating the hook through the ring, means for shifting the path of reciprocation of the hook so that it passes to one side of the ring, and means for looping a cord onto the crocheting hook in correlation with the reciprocation of the hook in each of its two paths to crochet a cord into a sheath about the ring.

16. In a machine for crocheting a sheath about a ring, means for supporting a ring to be sheathed, a reciprocating crocheting hook, means for reciprocating the crocheting hook through the ring on alternate strokes of the crocheting hook in one direction, means for shifting the path of reciprocation of the hook on the intervening alternate strokes in the same direction to cause the crocheting hook to pass to one side of the ring on said intervening alternate strokes, and means for looping a cord around the crocheting hook in correlation with the reciprocation thereof.

17. The method of crocheting a sheath about a ring which comprises reciprocating a latch type crocheting hook, shifting the path of reciprocation on alternate strokes of the hook in the same direction, positioning a ring between the two paths of motion so that on alternate forward strokes the hook passes through the ring and on the intervening alternate strokes the hook passes the ring on the outside thereof, looping one continuous thread around the hook each time it passes the ring, moving the previous loop on the crocheting hook past the latch upon the commencement of each forward stroke after the completion of a previous rearward stroke, making alternate rearward strokes of insufficient length to retract the needle from the loop previously left past the latch so that upon the next forward movement a second loop is left on the crocheting hook past the latch, and making the intervening alternate rearward strokes of a greater length and sufficient to draw the hook through both loops previously formed on the crocheting hook past the latch so that upon the subsequent forward movement of the crochet hook the loop on the hook is positioned past the latch for the next stitch.

18. The method of crocheting a sheath about a core which comprises passing a cord through a looper and continuously rotating the looper, reciprocating a crocheting hook through one for-

ward and one rearward reciprocation for every revolution of the looper and in a direction towards and away from the rotating looper but in the path of movement of the cord from the looper, shifting the path of reciprocation of the crocheting hook on alternate strokes of the hook in the same direction, and positioning a core to be sheathed between the two paths of motion of the crocheting hook.

19. The method of crocheting a sheath about a core which comprises reciprocating a crochet hook in a direction substantially axially of the hook, rotating the hook about an axis substantially parallel to the longitudinal axis of the hook

so that alternate reciprocations of the hook in the same direction are in different paths, positioning a core to be sheathed between the two paths of motion, and looping a cord around the crocheting hook in timed relation to the reciprocation thereof.

20. The method of crocheting a sheath about a core which comprises reciprocating a crocheting hook, shifting the path of reciprocation on alternate strokes of the hook in the same direction, positioning a core to be sheathed between the two paths of motion, and rotating a looper to move a crocheting cord over the needle each time that the needle is adjacent its forward position.
